LIGHTING FIXTURE

Vearl S. Wince, Newark, Ohio, and Carl X. Meyer, St. Louis, Mo., assignors of one-half to Holophane Company, Inc., New York, N.Y., a corporation of Delaware

Continuation of design application Ser. No. 78,693, Feb. 19, 1964. This application May 18, 1965, Ser. No. 85,338

Term of patent 14 years

(Cl. D48-23)

FIG. 2.

FIG. 3.

FIG. 4.

FIG. 1 is a perspective view of the lighting fixture showing my new design;

FIG. 2 is an enlarged end view of the lighting fixture;

FIG. 3 is a side view, a portion broken away for convenience of illustration; and

FIG. 4 is a top view thereof.

The undisclosed end is the same in appearance as the end shown.

This is a continuation of design application Serial No. D. 78,693, filed February 19, 1964, and now abandoned.

The dominant features of the design reside in the portions shown in the full lines.

We claim:

The ornamental design for a lighting fixture, substantially as shown and described.
